UNITED STATES PATENT OFFICE.

ARTHUR E. CHAPPELL, OF WAUKEGAN, ILLINOIS.

SURFACING MACHINE.

Application filed December 6, 1922. Serial No. 605,179.

To all whom it may concern:

Be it known that I, ARTHUR E. CHAPPELL, a citizen of the United States, residing at Waukegan, in the county of Lake and State 5 of Illinois, have invented certain new and useful Improvements in Surfacing Machines, of which the following is a specification.

This invention pertains to floor dressing 10 or surfacing machines, such as are employed to produce a smooth surface on floors, bowling alleys, and the like, and aims to improve upon machines of this character, particularly with respect to the means for maintaining the surfacing cylinder in operative 15 engagement with the floor.

Machines of this character have heretofore been made in which the surfacing cylinder or roll was adjustably mounted upon 20 the frame so that it could be adjusted toward or from the floor to give the desired depth of cut. Furthermore, machines have been designed in which the frame, or a portion thereof, carrying the surfacing cylinder, 25 has been provided with adjusting mechanism by which the position of the cylinder could be adjusted. All of such machines, however, possess such rigidity and inflexibility that the surfacing cylinder is 30 not permitted to accommodate itself to various conditions of the floor, and if the travel of the machine is stopped, the cylinder makes a groove or at least a mark where it continues to operate for any 35 considerable period of time.

One of the purposes of my present invention is to provide mechanism which will be under the constant control of the operator, and whereby the pressure of the surfacing cylinder upon the floor or other surface being worked can be regulated and increased or diminished at will as the machine is traveling along. The operator is therefore able to feel the irregularities and 45 high spots in the floor and can increase the pressure of the surfacing cylinder when required, or can diminish it when low spots are encountered; and furthermore, when turning or stopping the machine, the cylinder can be lifted from the floor without the necessity of disturbing its adjustments or of manipulating a normally locked adjusting lever.

Another purpose of the invention is to 50 provide a machine of the character indicated, which will be capable of accurate ad-

justment and control; one in which the surfacing cylinder will be yieldingly urged into contact with the surface being worked; and one which will be simple in construction, economical to manufacture, and accurate and efficient in operation.

To facilitate an understanding of my invention, I have illustrated on the accompanying drawings a preferred embodiment 65 thereof, and referring to the drawings:

Fig. 1 is a side elevation of a machine embodying my invention;

Fig. 2 is a rear elevation thereof;

Fig. 3 is a sectional view on the line 3—3, 70 of Fig. 2; and

Fig. 4 is a fragmentary sectional view on the line 4—4 of Fig. 1.

From an inspection of the drawings it will be observed that my improved machine 75 comprises a frame structure 5, preferably of box-like construction, adapted to accommodate the dust delivering fan 6 on the inside thereof, and to carry the driving motor 7 which is mounted on the top of the frame and connected by a driving chain 8 with the sprocket wheel 9 of the fan and the driving sprocket wheel 11 of the surfacing cylinder 12. This cylinder may be mounted in any preferred manner, but is illustrated herein as carried between the forward ends of a pair of arms 13, extending respectively through front and rear guide members 14 and 15, in which these arms are yieldingly retained by buffer blocks 16 80 adapted to be adjusted by adjusting screws 17.

The frame is carried principally by a pair of wheels 18 mounted upon a transversely extending shaft 19, which is disposed substantially midway between the ends of the frame structure so that the frame is nearly balanced thereon, the rear end being slightly heavier so that the frame tends to tilt downwardly at the back, and the wheels being of sufficient height to permit a degree of tilting of the frame, which will bring the surfacing cylinder into contact with the floor, or clear it some distance from the floor, as shown in Fig. 1, in which position the cylinder is of course inoperative.

To the rear end of the frame there is rigidly attached an upwardly and rearwardly projecting bar or pole 21, provided at its upper end with a handle 22 disposed in accessible position to the operator, who walks behind the machine. In order to be

accessibly positioned, the starting and controlling box 23 of the motor is preferably mounted upon this bar, as shown in Fig. 1.

For the purpose of tilting the frame about the axle 19, so as to urge the surfacing cylinder against the floor with any desired degree of pressure, I have provided at the rear end of the frame auxiliary supporting caster wheels 24, rotatably mounted in ball bearings 25, which are carried by a cross-bar 26. The ends of this cross-bar are engaged and adapted to vertically slide in guideways 27 formed in the rear ends of the side members of the frame; and to permit of a considerable latitude of vertical movement, the ends of the bar 26 are provided with upwardly projecting guide portions 28 adapted for relative vertical movement with respect to the guides 27, as will be apparent from Figs. 2 and 3.

Upon the bar 21, in proximity to the handle 22, there is pivotally mounted at 29 a hand lever 31, which extends beneath and in the general direction of one end of the handle, the short end of this lever being adjustably connected by a screw clamp 32 with the upper section 33 of a connecting rod, the lower section 34 of which is connected by a bolt 35 with the bar 26. It will be apparent that by swinging the lever 31 from the full line to the dotted line position shown in Fig. 2, the rear end of the frame will be elevated, thus depressing the surfacing roll into engagement with the floor, and upon release of this lever the frame will tilt in the opposite direction to clear the surfacing cylinder from the floor.

In order to provide for flexibility independently of the movement of the lever 31, which permits a limited tilting movement of the frame, I have interposed between the sections 33 and 34 of the thrust rod a coiled expansion spring 36 (Fig. 4). A sleeve 37, secured to one of the rod sections by a pin 38, surrounds the spring and receives the opposed end of the other rod section, which is equipped with a pin 37 adapted to slide in a slot 39 formed in one side of the sleeve. A downward thrust of the rod section 33 will therefore be yieldingly transmitted to the section 34, and consequently to the auxiliary caster wheels 24, and any slight vertical vibratory movements of the surfacing cylinder are accordingly absorbed by the spring instead of being transmitted in full force to the hand of the operator, which is grasping the lever 31.

In the operation of my machine the operator grasps the handles 22 with both hands, the fingers of one hand at the same time grasping the lever 31 and pulling it upwardly toward the handle 22. This movement of the lever exerts a downward thrust upon the caster wheels, which results in tilting the rear end of the machine

upwardly, and the forward end downwardly to engage the surfacing cylinder with the floor. As the machine progresses across the floor, any irregularities in the floor surface may be detected by the operator by the feel of the lever 31, and he may therefore increase the pressure of the cylinder when high spots are encountered, or relieve the pressure when low spots are encountered. The surfacing cylinder is therefore at all times under the direct control and manipulation of the operator, who is able to regulate the pressure of the cylinder to meet the requirements and conditions of the surface being worked. When the travel of the machine is to be stopped or when turning around, the cylinder can be cleared from the floor by simply releasing the lever 31. The operator is therefore not obliged to either disturb the adjustments of the cylinder or to release and manipulate a normally locked adjusting lever, as is customarily necessary in machines of this general character.

It is believed that the principles and the advantages of my invention will be understood without further description, and it should be manifest that it is capable of embodiment in constructions differing materially in their details from those illustrated and described, without departing from the scope of the invention, as defined in the following claims.

I claim:

1. In a surfacing machine the combination of a frame structure, a surfacing cylinder mounted on the forward end thereof, supporting wheels intermediate the ends of said frame, a handle connected with the rear end of the frame, a bar having upturned ends slidably connected with the rear end of said frame, a caster wheel supporting said bar, a hand lever adjacent said handle, and a connection between said lever and said bar whereby a relative vertical movement between said caster wheel and the rear end of said frame may be imparted upon manipulation of said lever.

2. In a surfacing machine the combination of a frame, supporting wheels intermediate the ends thereof about which said frame is adapted to tilt, a surfacing tool at the forward end of said frame, a bar slidably associated with the rear end of said frame, a caster wheel supporting said bar, a handle connected with the rear end of the frame, a lever pivotally mounted in position to be grasped by the hand of the operator engaging said handle, and a connection between said lever and said bar for regulating the vertical position of said bar with respect to the rear end of said frame.

3. In a surfacing machine the combination of a frame, supporting wheels intermediate the ends thereof, a transversely ex-

tending bar slidably associated with the rear end of said frame, a pair of caster wheels supporting said bar, a handle rigidly connected with the rear end of said frame, a 5 controlling lever disposed in proximity to said handle, and a yielding connection between said lever and said bar.

4. In a surfacing machine the combination of a frame, a pair of main supporting 10 wheels about which said frame is adapted to tilt, a pair of caster wheels slidably associated with the rear end of said frame, a handle, a controlling lever in proximity to said handle, and a yieldable connection between 15 said lever and said caster wheels.

5. In a surfacing machine the combination of a frame, a pair of supporting wheels therefor about which the frame is adapted to tilt, a caster wheel slidably associated 20 with the rear end of said frame, a bar rigidly

connected with said frame, a handle carried by the bar, a lever pivotally mounted on said bar in proximity to said handle, and a connection between said lever and said caster wheel, including a spring providing resiliency between said caster wheel and said lever. 25

6. In a surfacing machine the combination of a frame, supporting means therefor about which said frame is adapted to tilt, 30 auxiliary supporting means slidably connected with the rear end of said frame, a bar rigidly mounted on the frame, a handle carried by the bar, a lever pivoted on the bar adjacent to the handle, a rod adjustably connected with said lever, a connection between said rod and said auxiliary supporting means, and a spring providing flexibility in said rod. 35

A. E. CHAPPELL.
